CLAIM

The ornamental design for a foot operated door pull as shown and described.

DESCRIPTION

FIG. 1 is a front, right and top perspective view of a foot operated door pull, showing our new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a perspective view of the foot operated door pull in a usable state, which illustrates the foot operated door pull installed on a cabinet door.

The dashed broken lines depict portions of the foot operated door pull that form no part of the claimed design. The dot-dash broken lines define the boundary of the claimed design and form no part of the claimed design.
